T. S. STEPHENSON

AIR VALVE

Filed Sept. 6, 1921

FIG. 1.

FIG. 2

FIG. 7

FIG. 4

Inventor
THOMAS S. STEPHENSON

By N. E. Gee

Attorney

UNITED STATES PATENT OFFICE.

THOMAS S. STEPHENSON, OF ALTOONA, PENNSYLVANIA.

AIR VALVE.

Application filed September 6, 1921. Serial No. 498,701.

To all whom it may concern:

Be it known that THOMAS S. STEPHENSON, a citizen of the United States, residing at Altoona, in the county of Blair and State 5 of Pennsylvania, has invented certain new and useful Improvements in Air Valves, of which the following is a specification.

This invention relates to internal combustion engines.

10 A primary object is to provide means for increasing the efficiency of the engine by conducting the gas collected in the crank case due to leakage around the pistons during the compression stroke back to the intake line.

15 Another object of the invention is to provide novel and practical means for accomplishing the above result to thereby also prevent the gas from mixing with the oil 20 in the crank case and thus adding greatly to the life of the motor and motor bearings.

25 A further object is to provide convenient controlling means whereby the gaseous mixture from the crank case can be readily cut off from the intake pipe at the option of the driver of the car.

30 A still further object is to provide a controlling means that will not rattle, leak gas or become disarranged on the car thus adding greatly to the life of the mechanism and to the car to which it is attached.

35 With these and other object in view which will be more readily apparent as the nature of the invention is better understood, the same consists, in the novel construction, combination and arrangement of parts as will be hereinafter fully pointed out, illustrated, and claimed.

40 It will be, of course, understood by those skilled in the art to which this invention belongs that the same is susceptible to various changes and modifications without departing from the spirit or scope of the invention, but a preferred and thoroughly practical embodiment of the invention is shown in the accompanying drawings in which—

45 Figure 1 is a perspective view of a gasoline engine of the Ford type having my invention applied thereto and showing the controlling rod extending upward.

50 Figure 2 is a plan view of my improved gasoline vapor controlling device which is adapted to be positioned between the flange 55 of the intake pipe and the carburetor.

Figure 3 is an end elevation of the parts shown in Figure 2 of the drawings.

Figure 4 is a side elevation of the parts shown in Figure 2 of the drawings.

Figure 5 is a plan view and Figure 6 is a 60 sectional view of the oil filling pipe used on the Ford cars, showing the manner of connecting the gas pipe to the oil filling pipe.

Figure 7 shows an end elevation of the valve arrangement similar to Figure 3 showing the position of the valve when closed, in dotted lines.

Similar reference numerals refer to similar parts throughout the several figures of the drawings.

In carrying the present invention into effect, it is not necessary to change or alter the present construction of the intake manifold where the device is intended to be used on old cars, and obviously with but little 75 change in design the same may be applied originally to new cars in the manner which will not change the functioning of the device nor its efficiency.

In the form of the invention shown in the drawings the same essentially comprises a 80 shiftable valve 1 which may be in the form of a disk having an offset ear 2 on the periphery thereof for receiving a manipulating rod 3, while one face thereof may be 85 formed with a substantially arc shaped recess 3^a.

The said valve 1 may be suitably held to the seat 4 in the support 5 by any suitable and convenient means such for example as the pivoted screw 6 which may compress a coil spring 7 in the manner indicated in Figures 2 and 4 to force the valve disk against the seat 4 with enough pressure to maintain a tight joint between the rotating valve body and its seat.

The support 5 which carries the valve 1 is preferably provided with a nipple portion 8 having an interior passage way 9, and is also provided with an extension 10 arranged at right angles to the nipple 8 and provided with an opening or passageway 11 also at right angles to the passageway 9. As will be observed from Figure 4 for example, the portion 10 of the support 5 is preferably made in the form of a gasket having the central opening 12 for registering with delivery conduit of the carburetor and the intake manifold of the engine, and is also provided with the openings 13 in the flange portions 14 for 110

receiving the usual bolts which couple the carburetor to the flanges of the intake manifold in the well known manner.

From Figures 1 and 2 it will be observed that the threaded nipple portion 8 cooperates with a thimble nut 15 to clamp one end of a pipe or conduit 16 thereto, the said pipe being adapted to tap the oil filling pipe 17 of the car by means of any suitable and practical coupling such for instance as indicated at 18 in Figures 5 and 6. As shown in Figure 1, the present device is applied to a motor of the Ford type, and as is well known, the oil pipe 17 thereof directly communicates with the crank case, and hence gas accumulating therein, due to leakage around the pistons, may be readily extracted through the oil pipe in the manner proposed.

As the present device is installed in the intake line it will be apparent that when the recess 3^a in the valve disk establishes communication between the passageways 9 and 11, that the gas or vapor caged within the crank case may be sucked up into the intake line through the pipe 16. When it is desired to cut off the supply of gas through the pipe 16 the valve disk 1 may be rotated by the connection 3 from the driver's seat so as to bring the recesses 3^a out of registration with the opening 11 and thus close the auxiliary intake line. For the purpose of limiting the movement of the valve disk 1 the support 5 may be provided with abutments or stop projections 5^a and 5^b respectively arranged 90° apart, as shown in Figures 3 and 7 of the drawings the said stop

projections being engaged by the angled or offset end of the rod 3, not shown, but which projects through the opening in the ear 2.

Without further description it is thought 40 that the many features and advantages of the invention will be readily apparent and it will of course be understood that changes in the form, proportion, and minor details of construction may be resorted to without 45 departing from the spirit of the invention or the scope of the appended claim.

I claim:

A valve device for the intake line of internal combustion engines including a body 50 adapted to be clamped between parts of said intake line, said body having an offset part provided with an opening communicating with another opening in the body which registers with the intake line, a depending valve seat member carried by said offset portion and also having a passageway adapted to communicate with the crank case of the engine, a disk cooperating with said valve seat member and having a recess for establishing 55 communication between said passageway of the offset portion and with the passageway which communicates with the crank case of the engine, fastening means including a spring for holding said disk to the valve 60 seat member, means for rotating said disk, and projections carried by said valve seat member for cooperating with said means to limit the arc of movement of the disk.

In testimony whereof I have affixed my 70 signature.

THOMAS S. STEPHENSON.
